ELECTRIC SWITCH

John Fowler, Stockport, England, assignor to
Metropolitan-Vickers Electrical Company Limited,
London, England, a British company

Application June 19, 1946, Serial No. 677,660
In Great Britain November 29, 1945

2 Claims. (Cl. 200—6)

1

This invention relates to electric switches and more particularly to improvements in polyphase tap-changing switches.

Tap-changing switches are often used for varying the ratio of a transformer. In many arrangements of this kind there is a double-pole switch per phase in which the current is carried by one pole when the other is to be moved from tap contact to tap contact, and vice versa, so that taps may be changed without interrupting the circuit. Heretofore, polyphase double-pole tap-changing switches have been relatively large because the two polyphase poles have been mounted in tandem and this has also required an extra amount of equipment for operating the two poles in the necessary step-by-step or follow-up manner.

In accordance with this invention a polyphase multi-pole tap-changing switch is provided in which the different poles are operated by concentric rotatable driving means, thereby effectively halving the length or height of the switch and also making it possible to use a much more compact driving mechanism because this mechanism can then be mounted at one end of the switch.

An object of the invention is to provide a new and improved electric switch.

Another object of the invention is to provide a compact light-weight polyphase tap-changing switch.

The invention will be better understood from the following description taken in connection with the accompanying drawing and its scope will be pointed out in the appended claims.

In the drawing Fig. 1 is a vertical sectional view of a switch embodying the invention, Fig. 2 is an enlarged elevation view of the outer of the two concentric operating members for the switch shown in Fig. 1, Fig. 3 is an enlarged elevation view of the inner of the two concentric operating members for the switch shown in Fig. 1.

Fig. 4 is a sectional view taken on line 4—4 of Fig. 1, and Fig. 5 is a circuit diagram of one of the phases of the switch illustrated in Fig. 1.

Referring now to the drawing and more particularly to Fig. 1, the switch is shown as comprising an insulating cylinder 1. Mounted circumferentially in a transverse plane through the cylinder are a plurality of fixed contacts 2 and in an adjacent transverse plane is another set of fixed contacts 3, these two sets of contacts being in a zone around the cylinder which is assigned to one phase, say, for example, phase A

of the switch. Similarly, there are sets of contacts 4 and 5 for phase B of the switch and sets of contacts 6 and 7 for phase C of the switch. For making selective contact with the circumferentially or circularly arranged sets of contacts 2, 3, 4, 5, 6 and 7 are respective movable contact arms 8, 9, 10, 11, 12 and 13. The movable contact arms 8, 10 and 12 are clamped relatively tightly to a tubular member 14 of any suitable insulating material. As shown, the movable contact arms 8, 10 and 12 may be clamped to the tube 14 by means of screws 15. The tube 14 is mounted coaxially and preferably concentrically with the cylinder 1. It is provided with three circumferentially extending slots 16, one of which is shown enlarged in Fig. 2. Mounted on the tube 14 are three slotted sleeves 17 which are freely rotatable relative to the tube and one of these sleeves is shown enlarged in Fig. 2. The slots in the tube 14 and sleeves 17 are in registration.

The movable contact arms 9, 11 and 13 are driven by a shaft 18 which is mounted inside the tube 14. This shaft is provided with three slots 19, one of which is shown enlarged in Fig. 3, and a separate key 20 is inserted in each slot 19.

The contact arm 9, which is the same as the contact arms 11 and 13, is shown in enlarged sectional view in Fig. 4 and it will be seen that this arm has a cap 21 which by means of bolts 22 can be clamped tightly around the relatively loose sleeve 17 on the tube 14. The key 20 serves to interconnect the shaft 18 with the contact arm 9 through the slots 16 so that the movable contact arms 9, 11 and 13 will rotate simultaneously with the shaft 18.

The angular extent of the slots 16 corresponds or is at least equal to the angular distance between adjacent fixed contacts on the cylinder 1.

The shaft 18 is journaled at the bottom in a bottom plate 23 which closes the end of the cylinder 1 and both the tube 14 and the shaft 18 extend through a top web or plate 24, the shaft 18 extending slightly beyond the end of the tube 14. A Geneva gear 25 is mounted on the upper end of the tube 14 and a Geneva gear 26 is mounted on the upper end of the shaft 18. These Geneva gears are driven by a common driver 27 having pins or lugs which are disposed 180 degrees thereon so that the shaft and the tube will be alternately rotated through the desired angular distance step by step in a follow-up manner. For example, the shaft 18 can first be rotated through the angular distance between

adjacent fixed contacts, which rotation will substantially span the slots 16. Then the tube 14 will be rotated through the same angle in a follow-up direction so as to permit a subsequent angular motion of the shaft 18 and this cycle may be repeated until the movable contact arms have traversed their respective circular rows of fixed contacts.

A suitable circuit for one phase of the switch is shown in Fig. 5 in which the set of movable contacts 2 is connected to spaced points in a transformer winding 28 and the set of contacts 3 is connected to a different set of spaced taps for the winding 28. The rotatable contact arm 8 makes electrical contact with a conductor 29 and the rotatable contact arm 9 makes electrical contact with a conductor 30. Conductors 29 and 30 terminate in contacts 31 and 32 respectively which are alternately engaged by a movable contact 32 of an arcing duty switch. As shown, current limiting resistors 33 and 34 are connected respectively between conductors 29-30 and intermediate fixed contacts 35 and 36 so that as the arm 32 is oscillated from one extreme to the other the current of the winding 28 is first limited by the resistors 33 and 34, as the case may be, before the current is interrupted and also circulating current from a short circuit of electrically adjacent fixed contacts is controlled by the resistance of resistors 33 and 34 in series when the movable contact 32 is in its mid-position.

With the sleeves 17 freely rotatable on the tube 14, and with the arms 9, 11 and 13 clamped tightly to the sleeves 17, the relative movement will be between the sleeves 17 and the tube 14. The arms 9, 11 and 13 are actuated by the keys 20 and the axial position of the arms 9, 11 and 13 is maintained by the keys 20. Obviously, however, this is not essential and it will readily occur to those skilled in the art that the sleeves 17 can be fixedly attached to the tube 14 and the arms 9, 11 and 13 can be rotatably mounted on the sleeves 17. This has the advantage that the flanges shown on the sleeves 17 in Fig. 2 will then fix the axial position of the arms 9, 11 and 13 and a larger area is obtained for the relatively moveable engaging surfaces.

While there has been shown and described a particular embodiment of this invention, it will be obvious to those skilled in the art that various changes and modifications can be made therein

without departing from the invention and, therefore, it is aimed in the appended claims to cover all such changes and modifications as fall within the true spirit and scope of the invention.

5 What I claim as new and desire to secure by Letters Patent of the United States, is:

1. A polyphâse multi-pôle per phase switch comprising, in combination, a rotatable shaft, a relatively rotatable sleeve on said shaft, a plurality of axially spaced circumferentially extending slots in said sleeve, separate rotatable contact arms relatively loosely mounted on said sleeve, separate means extending through said slots for respectively attaching said arms to said shaft for simultaneous rotation therewith, additional rotatable contact arms respectively axially adjacent the first-mentioned contact arms, said additional contact arms being attached relatively rigidly to said sleeve for simultaneous rotation therewith, and respectively separate sets of cooperating fixed contacts for said contact arms.
- 15 2. A three-phase double-contact finger ratio adjuster switch comprising, in combination, an insulating cylinder, separate sets of contacts disposed circumferentially around the inside of said cylinder in at least three different axially spaced bands, a rotatable contact carrying assembly mounted coaxially of and inside said cylinder, 20 said assembly comprising a shaft inside a tubular sleeve, three contact arms mounted on said sleeve for rotation therewith and for cooperation respectively with different ones of said sets of contacts, circumferentially extending slots in said 25 sleeve respectively adjacent said contact arms, additional contact arms mounted on said sleeve for relative rotation therewith, means extending through said slots for rotating said additional contact arms by means of said shaft, and means for alternately rotating said sleeve and shaft through angles of the order of the circumferentially extent of said slots.
